Rigloo are you rescue ready, announced in YouTube on Jun. 23, 2019 [online], [site visited Nov. 1, 2022], Available from the internet URL: https://www.youtube.com/watch?v=jzd6u-NmO_U (Year: 2019).*

Primary Examiner — Christian P. McLean*Assistant Examiner* — Jasmine L. Comedy(74) *Attorney, Agent, or Firm* — MaxGoLaw PLLC(57) **CLAIM**

The ornamental design for a shelter, as shown and described.

DESCRIPTION

FIG. 1 is a perspective view of the shelter, where dashed lines denote stitching intrinsic to the design;

FIG. 2 is a front view of the shelter depicted in FIG. 1;

FIG. 3 is a left side view of the shelter depicted in FIG. 1, where dashed lines denote stitching intrinsic to the design;

FIG. 4 is a back view of the shelter depicted in FIG. 1;

FIG. 5 is a right side view of the shelter depicted in FIG. 1, where dashed lines denote stitching intrinsic to the design;

FIG. 6 is a top view of the shelter depicted in FIG. 1, where dashed lines denote stitching intrinsic to the design; and,

FIG. 7 is a bottom view of the shelter depicted in FIG. 1. The drawings contain symbolic break lines in FIGS. 1, 3, and 5-7. The break lines and portions between the break lines form no part of the claimed design.

1 Claim, 7 Drawing Sheets(56)
